UNITED STATES PATENT OFFICE

GEORGE M. PELTON, OF MILWAUKEE, WISCONSIN, ASSIGNOR TO THE FILER & STOWELL CO., OF MILWAUKEE, WISCONSIN, A CORPORATION OF WISCONSIN

SAWMILL CARRIAGE

Application filed March 19, 1929. Serial No. 348,322.

This invention is directed to an improvement in means for limiting the movements of the dogs of a saw mill carriage to prevent the dogs from reaching the saw line without in any way interfering with the usual limit travel of the knee toward the saw line.

The invention is particularly applicable to that type of dogging mechanism in which the dogs are adapted for either a minimum projection beyond the face of the knee or a maximum projection beyond the face of the knee, the position of the dogs being manually controlled and adjusted at will to suit the particular conditions of dog use. Obviously, where the dogs are capable of minimum or maximum projection beyond the face of the knee, any means to limit the movement of the dogs toward the saw line to thereby prevent the dogs from entering the saw line must take into consideration the different relative positions of the dogs relative to the face of the knee, for if the knee was interrupted in its travel toward the saw line so as to prevent the dogs at their minimum projection from being engaged by the saw, obviously the dogs when projected to their maximum degree would reach the saw line before the forward movement of the knee was completely interrupted. Conversely, if the knee interruption was provided for to take care of the dogs when projected their maximum distance beyond the face of the knee, the knee travel would be stopped long before the dogs when at their minimum projection could enter the saw line. Thus, no positive stop cooperating with the knee alone can properly take care of both conditions.

Heretofore, the dogs and the dog operating means of the type to which this invention is directed have been mounted on the outside of the knee, but it has been found desirable to so construct the parts as to mount the essential dog operating elements and the dogs within the knee. This arrangement has brought about the necessity of providing improved means adapted for cooperation with the housed dogs, to limit their movement toward the saw when in either their maximum or minimum position.

Therefore, it is the primary object of the

present invention to provide a stop for the movement of the dogs toward the saw line, which stop, when in operation, interrupts the movements of the dogs toward the saw line and holds the points of the dogs fixed or stationary without interrupting the movement of the knee. The knee under this construction will continue to move forward to its normal limit stop while the dogs, being interrupted by the stop of this invention, will be proportionally withdrawn back into the knee as the knee advances.

The invention is illustrated in the accompanying drawings, in which:

Figure 1 is a view in side elevation showing the knee provided with the improved adjustable limit means.

Figure 2 is a perspective view showing the limit means connected to the guide rod for the unit support and adjustment of the dogs.

Figure 3 is a view in front elevation of the knee equipped with the limit means.

Figure 4 is a similar view showing a slight modification.

Figure 5 is a view in elevation, partly in section, of a slightly modified form of the invention.

The improved dog limiting means is designed particularly for use in that type of dogging mechanism wherein one or more dog units are mounted upon a guide bar 1 which is adjustable with respect to the face of the knee to thereby cause the operating points of the dogs to project to a minimum or maximum distance beyond the face of the knee, in order to cooperate with a particular type of material, such mechanism, for example, being shown in an application filed by me May 19, 1927, Serial No. 192,723.

In the form illustrated in Figures 1, 2 and 3, this guide bar which is arranged within the knee, is connected adjacent its upper and lower ends to cranks 2 operating wholly within the knee and rigidly connected to crank shafts 3 mounted in bearings 4 formed in the side of the knee, such shafts being provided at their outer ends with rigid arms 5 connected for simultaneous and similar movement through a bar 6. One of the arms 5, as the upper one, is connected to the piston rod

8 of a piston operative in a cylinder 9 and constituting a motor mechanism to be suitably controlled by the admission of a pressure medium to turn the cranks 2 on their pivotal supports and thereby move the bar 1 and the dog units toward and from the face of the knee to provide for minimum or maximum projection of the dogs relative to the face of the knee.

10 In the form illustrated in Figures 1, 2 and 3, the arms 5 are pivotally supported on the knee and the cranks 2 are connected to the bar 1 by crank pins 10 operating through an arcuate slot 11 in the side of the knee to permit the play of the lower pin 10 in the adjustment of the guide bar.

15 The stop mechanism includes an abutment or stop 12 mounted on the head block in the path of movement of a hook or lug 13 at the free end of a bar 14, the opposite end of which is connected at 15, to the outer end of lower crank pin 10, outside of the knee. For convenience, a portion of the bar 14 adjacent and including the hook or lug 13 is projected in 20 parallelism with the plane of movement of the knee, the remaining length of the bar being inclined upwardly leading to its connection at 15. If desired and as preferred, the straight portion of the bar 14 rests in a 25 guide 16 carried on the knee to prevent displacement of this bar while approaching and during its engagement with the limiting stop 12.

30 In the form of the invention shown in Figure 4, the lower crank 2 of the preferred form is rigidly connected to the crank shaft 22 but its crank pin 23, which forms the pivotal connection with the guide bar 1, does not extend through the side of the casing. In lieu of 35 the pivot pin forming the connection for the bar 14, I mount a sleeve 24 on the shaft 22, from which, outside of the knee, extends an arm or lever 25 and at the outer end thereof is a pivot pin 26 in alignment with the crank 40 pin 23, connecting the crank 2 to the guide bar 1. To the pivot pin 26 is pivotally connected the end of the bar 14.

45 The operation of both forms is identical in so far as the dog limiting means is concerned. In this connection, attention is called to the fact that the usual head block is provided with front stop 20 which is engaged by the knee stop 21 in the movement thereof and positively limits the knee in its advance 50 toward the saw line to avoid interference with the saw. The present dog limiting means operates wholly independently of the knee stops and is without any effect on the movement of the knee in its usual limit travel in 55 either direction. So far as the dog mechanism is concerned, it will be understood that, through proper control of the motor mechanism 9, the guide bar 1 is adjusted so as to set the dogs for the maximum or minimum 60 projection beyond the face of the knee. If 65

70 this guide bar has been adjusted for the minimum projection of the dogs, for example, it is apparent that should the knee, in its movement toward the saw line, move the dogs into the path of the saw before the knee reached its forward limit stop, damage to the saw and danger to the operators would undoubtedly ensue. With the guide bar 1 adjusted for such minimum dog projection, however, it

75 will be noted that bar 14 is correspondingly moved rearwardly with respect to the face of the knee and to an extent in exact accordance with the adjustment of the guide bar. Therefore, the hook or lug 13 of the bar 14 is moved farther from the face of the knee and 80 hence the knee is permitted a definite advance movement toward the saw line before the hook or lug 13 engages the limit stop 12. If the guide bar 1 had been adjusted by the 85 motor mechanism 9 to an advance position, thereby providing for the maximum projection of the dogs, it is apparent that the bar 14 and hook 13 will be correspondingly advanced toward the face of the knee in direct 90 accordance with the dog adjustment and that, therefore, in the advance of the knee, the hook 13 would engage the stop 12 at a definite point in the advance of the knee, but, of course, at a point farther removed from the saw line than where the dogs had been projected only 95 to their minimum distance as in the instance above noted. As the knee advances, the hook 13 engages the stop 12 at the particular 100 predetermined position which is that position at which the dogs, whether in advanced, 105 retracted or intermediate position, have not yet reached the saw line. This engagement of the hook 13 and stop 12 arrests the forward movement of the guide bar with the knee, 110 that is to say the guide bar cannot advance 115 with the knee while the latter is not interrupted because it has not yet reached its own limit stop on the head block. By this arresting of the unit movement of the guide bar and knee, there is a relative movement produced 120 between these parts, that is the guide bar is held stationary while the knee continues to advance. This will, of course, immediately effect a withdrawing operation of the dogs, 125 that is the dogs will be gradually withdrawn into the knee as the knee continues its advance toward the saw line.

130 Merely for illustrative purposes, we will assume that the knee stop on the head block 120 interrupts the movement of the knee while the face of the knee is one inch from the saw line. We will further assume that the extreme restricted or minimum position of the dogs is three-quarters of an inch in advance 135 of the face of the knee and that their maximum projection may be anything from three to five inches in accordance with the work being handled. With the knee advancing the log toward the saw line and the dogs, say, projected four and one-half inches beyond the 140

face of the knee, the relation of the parts is such that the hook 13 will engage the stop 12 when the free ends of the dogs are, say, one-quarter of an inch from the saw line. Obviously, the dogs cannot advance beyond this limit while the knee may continue to move to a position within one inch of the saw line. After the movement of the dogs has been interrupted by the cooperation of the hook 13 and stop 12, and the knee continues to advance, the dogs are gradually retracted relative to the face of the knee, that is the knee advances toward the free ends of the dogs, gradually reducing the distance between the free ends of the dogs and the knee until, when the knee reaches its limit stop, the dogs will have been withdrawn into the knee to leave the minimum dog projection, three-quarters of an inch in the particular instance cited, and still one-quarter of an inch from the saw line. Thus, as the parts reach their minimum spacing from the saw, where in the instance cited, the knee is stopped one inch from the saw line and the dogs are projected three-quarters of an inch beyond the face of the knee, it is apparent that there is no possible interference between the dogs and saw.

The dog stopping mechanism of the present invention is of course to be applied on every knee and will be effective as the particular knee advances. It is of course apparent that with idle knees, that is those knees of the carriage with which the log is not engaged, the idle dogs will be gradually withdrawn into the knee as the knee advances to thereby prevent the dogs from encroaching on the saw line. With those knees in which the dogs are actually engaged in the log, the stop is of course equally as effective. In these instances, however, the dogs being embedded in the log, the automatic stop will serve to prevent further advance of the dogs toward the saw line and under these circumstances, if the stop became effective during the travel of the knee toward the saw line, the effect of the stop in the movement of the dogs would be interrupted and the dogs freed from the log. The stop would of course function as a stop in connection with the dogs on those knees with which the log was engaged as well as where the dogs were idle, so that for the purpose of the invention, the stop is completely effective to prevent the dogs reaching the saw line and this whether the particular dogs are idle or engaged in a log.

I am aware of the dog stopping mechanism disclosed in the application for patent of G. E. Schnell, Serial No. 156,667, filed December 23, 1926, and make no claim broadly to mechanism for preventing dogs movable to a maximum and minimum distance from the knee, contacting with a saw, but rather to the particular character of the structure herein shown and described.

65 The invention as applied to enclosed dogs

and enclosed dog operating mechanism of the type described effectually precludes a setter projecting the dogs into the path of the saw. By connecting the limiting bar 14 to the pivotal connection 15 between the crank and the movable guide bar 1, the lug 13 and stop 12 are at all times in such relative position as will insure of the movement of the dogs being limited to prevent them passing over the saw line.

In Figure 5 there is shown a somewhat modified form of the invention wherein the guide bar, similar to the guide bar 1 of the first form, and here indicated at 27, is connected to the down-turned arms 28 of cranks 29 mounted and operating within the knee. These cranks have rearward projections 30 connected for simultaneous movement by a bar 31. The upper crank extension 30 is connected to the piston of the power means, as in the preferred form. The down-turned extension 28 of the lower crank is, in the form illustrated in Figure 5, projected beyond the connection of such extension and the guide bar 27 to form a crank arm 32, the lower end of which depends below the knee and moves in the path of a stop 33 secured on the head block at an appropriate point in the travel of the knee toward the saw line. Front and rear adjustable stops 34 and 35 are mounted in the knee in the path of movement of the crank extension 28. These stops, which as illustrated are in the form of headed rods threaded in a suitable mounting for the longitudinal adjustment of the stops, determine the respective positions of the crank extension 28 when the dogs are projected to their maximum or minimum positions.

In effective operation, the form illustrated in Figure 5, in so far as the control of the dogs is concerned, is identical with the form shown in Figure 1; that is to say, with the dogs projected to their maximum position, the crank arm 32 will occupy the position shown in full lines in Figure 5. With the dogs in this advanced position and the knee moving toward the saw line, it will be apparent that if such relation of parts and continued movement of the knee is permitted, the dogs would cross the saw line before the knee met the usual fixed stop provided on the head block and indicated at 20 in Figure 1. With the crank arm 32 in the position indicated in full lines in Figure 5, it is understood that said arm would engage the stop 33 before the knee engages the stop 20. Therefore, as the knee continues to advance, it will be apparent that the cranks 28, by reason of the cooperation of the arm 32 and stop 33, will be swung rearwardly, moving the dogs from their maximum advanced position toward and eventually into their minimum advanced position.

With the dogs in their minimum advanced position, the arm 32 of the crank is in the position indicated in dotted lines in Figure 130

5, and under these circumstances will engage the stop 33 simultaneously with the engagement of the knee stop 21 with the head block stop 20. It is of course understood that in 5 the minimum projected position of the dogs, the knee is interrupted in its forward movement by cooperation of its stop 21 with the head block stop 20 (as shown in Figure 1) before the dogs in such minimum projected 10 position can reach the saw line.

The front and rear stops 34 and 35 for the cranks, it being understood that such stops are provided for both the upper and lower cranks, have an important function in connection 15 with this type of apparatus. It will be appreciated that when the dogs are in maximum projected position, the crank arms 28 connected to guide bar 27 bear squarely in contact with the forward stops 34. This 20 insures a firm, rigid bearing point for the crank, relieves the power means of all strain, prevents any possibility of lost motion in the operating parts, and thereby insures more perfect lumber in the cutting operation. 25 With the dogs in their minimum projected position, the crank extensions 28 engage the rear stop 35, with the same effect as in the engagement with the forward stop in so far as relieving the power means of strain and 30 preventing lost motion in the parts.

This application is in part a continuation of my application filed May 25, 1927, Serial No. 194,184.

What is claimed to be new is:

- 35 1. In a saw mill carriage, a knee, a dog mounting, cranks connecting the dog mounting and knee to permit movement of the mounting toward the face of the knee, dogs carried by the mounting, a stop on the carriage, and an arm forming a rigid extension of one of the cranks and adapted to depend in the path of the stop when the dogs are projected to their maximum extent.
- 40 2. In a saw mill carriage, a knee, a dog mounting, cranks connecting the dog mounting and knee to permit movement of the mounting toward and from the face of the knee, dogs carried by the mounting, a stop on the carriage, and an arm forming an extension of one of the cranks and adapted to depend in the path of the stop and to engage said stop in the movement of the knee toward the saw line to thereby limit the further movement of the dogs toward the saw line
- 45 3. In a saw mill carriage, a knee, a dog mounting, cranks connecting the dog mounting and knee to permit movement of the mounting toward and from the face of the knee, dogs carried by the mounting, a stop on the carriage, and an arm forming an extension of one of the cranks and adapted to depend in the path of the stop and to engage said stop in the movement of the knee toward the saw line to thereby limit the further movement of the dogs toward the saw line
- 50 4. In a saw mill carriage, a knee, a dog mounting, cranks connecting the dog mounting and knee to permit movement of the mounting toward and from the face of the knee, dogs carried by the mounting, a stop on the carriage, and an arm forming an extension of one of the cranks and adapted to depend in the path of the stop and to engage said stop in the movement of the knee toward the saw line to thereby limit the further movement of the dogs toward the saw line
- 55 5. In a saw mill carriage, a knee, a dog mounting, cranks connecting the dog mounting and knee to permit movement of the mounting toward and from the face of the knee, dogs carried by the mounting, a stop on the carriage, and an arm forming an extension of one of the cranks and adapted to depend in the path of the stop and to engage said stop in the movement of the knee toward the saw line to thereby limit the further movement of the dogs toward the saw line

In testimony whereof I affix my signature.
GEORGE M. PELTON.
